UNITED STATES PATENT OFFICE.

ROSA A. BLISS, OF OMAHA, NEBRASKA.

DESIGN FOR A HAT-SUPPORTING BAND.

SPECIFICATION forming part of Design No. 30,327, dated March 7, 1899.

Application filed February 8, 1899. Serial No. 704,985. Term of patent 3½ years.

To all whom it may concern:

Be it known that I, ROSA A. BLISS, a citizen of the United States, residing at Omaha, in the county of Douglas and State of Nebraska, have invented and produced a new and original Design for Hat-Supporting Bands, of which the following is a specification, reference being had to the accompanying drawing, forming a part hereof.

5 The drawing shows in perspective a hat-supporting band embodying my design. It forms an approximately oval and frusto-con-

ical structure; but it is divided or discontinuous at C. The band is wider and also more inclined at one end A of the oval than at the other end B.

What I claim is—

The design for a hat-supporting band, substantially as shown and described.

ROSA A. BLISS.
